UNITED STATES PATENT OFFICE.

H. RAYMOND ADAMS, OF MARSEILLES, ILLINOIS.

REGULATOR FOR PUMPING-WINDMILLS.

SPECIFICATION forming part of Letters Patent No. 331,363, dated December 1, 1885.

Application filed September 19, 1885. Serial No. 177,560. (No model.)

To all whom it may concern:

Be it known that I, H. RAYMOND ADAMS, a citizen of the United States of America, residing at Marseilles, in the county of La Salle 5 and State of Illinois, have invented certain new and useful Improvements in Regulators for Pumping-Windmills, of which the following is a specification, reference being had therein to the accompanying drawings.

10 This invention relates to certain improvements in regulator attachments for pumping-windmills when the pump in use is of the class called "force-pumps," and used for forcing water at a distance from the windmill into a 15 tank or for forcing water up into an elevated tank, the construction and operation of which are fully set forth and explained in the following specification and claims, reference being had to the accompanying drawings, which form 20 a part of this specification.

Referring to the drawings, Figure 1 represents a vertical section of a windmill-tower having its upper portion broken away, of a water-tank arranged in said tower, and of a 25 well, and a side view of a pump arranged to take water from said well, of a pipe leading from said pump to the tank above, of a regulator located in the well and connected with the pump-pipe, and of the mechanism for 30 governing the regulator. Fig. 2 is a side view of the regulator-cylinders. Fig. 3 is a central vertical longitudinal section of the regulator-cylinders. Fig. 4 is a side view of the tank-valve, the ports of which are opened and closed 35 by the lowering and raising of the tank-float to govern the regulator. Fig. 5 is a side view of the tank-float and its parts which connect it with the tank-valve, and Fig. 6 is a cross-section of the tank-valve and a side view of 40 its pivoted weighted lever.

A represents a water-tank arranged in the tower of a windmill, having a central tube fixed therein, through which the pumping-shaft and regulating-wire of the windmill pass. 45 P represents a pipe, which is connected with the pump and arranged in such manner as to discharge water forced through it into tank A.

J represents the regulator-cylinders, and are in Fig. 1 arranged in the well and connected 50 with pipe P by means of a suitable pipe and pipe-couplings.

F represents the regulating wire or cord of a windmill, suspended from the operative parts of a windmill, and secured at its lower end to a plunger-piston, R, of the regulator-cylinder J'. 55

G represents a cord or small chain, which is also secured to the plunger-piston R of the regulator J, and passed up and over one or more pulleys, and has a weight, H', secured to its depending loose end. 60

E is a valve, which is connected with pipe P at its discharge end, and so constructed and arranged that the water discharged from the pipe P must pass through its ports d a. (See Figs. 1, 4, and 6.) 65

D is a weighted lever pivotally secured to the partially-rotating case E' of valve E, between a pair of ear-lugs, (see Figs. 4 and 6,) and has an integral side arm, D', which is perforated at its outer end. A pair of lugs, e e, 70 (see Fig. 6,) of said lever prevent it from any great independent movement, but permit it to be independently moved to pass a dead-center, after which one of its lugs e will engage case E', and thereby partially rotate said case to bring its ports a in or out of line with the ports d of the central stationary core, Z, of said valve, which core or pipe is closed on its outer end by means of the screw-cap a'. 75

B is a float having a screw-threaded rod, K, 80 suspended from its under side by means of a coil-spring, M. This rod K passes through the perforation in arm D', and has turned upon it a pair of nuts, N and C, one above and one below said arm, (see Figs. 1 and 5,) and are 85 for the purpose of engaging said arm to move lever D, so its weight will work valve E.

K' is a weight suspended from bar K to insure positive working of the parts.

The regulating-cylinders are shown more 90 particularly in Figs. 2 and 3, and consist of a short cylinder, G², of a cylinder, J', connected with said cylinder G² by means of a web so constructed as to form a port, (shown at I,) of a cylinder, J'', secured to and depending 95 from the lower part of cylinder J', of a depending neck, Q, secured to the lower part of cylinder G² by means of screws through flanges integral with said parts, of a depending coil-spring, O, arranged over said depending neck 100 Q, and suspended from the hooked arms O' O' of the flange of neck Q, of a plunger, H, ar-

ranged within cylinder G^2 and having a depending stem, S, screw-threaded at its lower end to take on the nut R' , of a stirrup, S', hooked on the lower end of spring O and having a central perforation through which stem S is arranged, so nut R' will rest against said stirrup, and of a plunger, L, arranged within cylinder J'' and having an upwardly-extending piston, R, arranged through the upper part of cylinder J' , and is made water-tight at that place by packing (shown at T') properly held to its place by means of the screw-threaded gland T.

The plunger L is constructed in two parts sleeved on piston R in such manner as to properly hold a pair of flanged packings, v v', between said parts by means of a nut turned on said piston against the lower part of said plunger.

20 The opening through neck Q is smaller than cylinder G^2 , for the purpose of forming a seat for plunger H when depressed, as shown in Fig. 3, and an annular packing, W, placed between the flanges of cylinder G^2 and neck Q, projects under plunger H, to make it watertight at that place when said plunger is depressed, as shown.

30 The face-packing U of plunger H is for the purpose of resting against the shoulders in the upper part of cylinder G^2 , to make it watertight at that place to prevent water from entering said cylinder from pipe P when under ordinary pressure when the plunger H is held in such position by coil-spring O.

35 G' is an ordinary elbow-pipe coupling for attaching the regulator to the discharge-pipe P.

The core Z of valve E has the ports d, and also has a female screw-thread cut in one end 40 for the purpose of attaching the valve to the screw-thread end of the discharge-pipe P, and also has a male screw-thread cut on each end, so the screw-cap a² and a collar, a', may be turned thereon, one at each end of the partially-rotating case E', in such manner as to 45 permit partial rotation of said case and to hold its ports a in a corresponding position with ports d.

50 The arrangement of the parts of said valve are such that ports a will when lever D is moved one way be midway between ports d of core Z, which will cut off the discharge of water from pipe P, and when lever D is reversed, ports a will be in line with ports d, so water 55 may be discharged through them.

By constructing the case E' and core Z in cylindrical form, and arranging their ports as shown with relation to each other, it matters not what the external or internal pressure 60 may be, case E' will at all times move with the same ease.

The operation of this device is as follows: When the water in the tank rises, it will elevate with it the float B. When nearly filled 65 with water, nut C on the depending rod K will engage with the extending arm of lever D',

causing it to throw the weighted lever D over and partially rotate case E' so its ports will be out of line with the ports of core Z, and thus arrest the discharge of water from pipe P. 70 The pump, continuing to operate after said valve closes, will increase pressure of water in pipe P to such extent as to overcome the resiliency of spring O and depress plunger H in cylinder G^2 below the port I, and permit 75 passage of water from pipe P into cylinder G^2 , from thence through ports I into cylinder J' above plunger L, and force it down to the lower end of cylinder J'' to the position shown in Fig. 3. The piston R of plunger L, being 80 attached to regulating-wire F, as described, will, when said plunger is thus forced down, pull the sails of the wind-wheel from the wind and stop further rotation of the wind-wheel. When the water in the tank is consumed down 85 to a certain point, nut N of rod K will engage with arm D' of weighted lever D, and throw it over in the opposite direction and rotate case E' so as to bring its ports in line with those in core Z, so that water in pipe P will 90 again discharge in the tank, and thus relieve the increased pressure of water in pipe P, which will in turn relieve the pressure on plunger H, so spring O will return said plunger to its proper position in the upper part of 95 cylinder G^2 , and thus prevent further discharge of water from pipe P into the regulator until valve E is again closed as before, so increased pressure in pipe P may again be produced. After plunger H passes above 100 port I the water in cylinder J'' is discharged back through port I and out through neck Q by means of plunger I being raised by weight 105 H', which connects with piston R of plunger L by means of the cord or chain G, as before 110 stated. When the piston R is thus raised, it permits the regulating-wire F of the windmill to return, so the sails of the windmill may again be turned to the wind to permit the mill to pump water into the tank.

110 The coil-spring M of the float B is for the purpose of giving ease to the movement of the immediate parts.

The cylinders G^2 and $J' J''$ are designed to be attached to pipe P, at any desirable place 115 along said pipe, in the manner shown in Figs. 1 and 2, and the tank A may be located in any other place than in the tower or at a distance from the tower. When water is forced to distant places or very high, the additional pressure 120 in pipe P brought to bear against plunger H of the regulator may be counterbalanced by turning down nut R', to give greater tension to spring O, so plunger H will resist greater pressure of water in pipe P.

125 By the use of this regulator the action on the sails of the mill is very prompt and quick, so they are turned to or from the wind almost instantly.

If desired, the float B may be used without 130 the coil-spring M, by being attached directly to the screw-threaded rod K.

Having thus described my invention, what I claim as new, and desire to secure by Letters Patent, is as follows, to wit:

1. The regulator attachment for pumping-windmills shown and described, consisting of the combination of the cylinders $J' J''$, having the plunger L and piston R, cylinder G^2 , having the piston H, depending stem S, neck Q, of smaller diameter than said cylinder, coil 5 spring O, having the stem S and hooks O', the said cylinders being connected by the web having the port I, the pipe P, having the valve E at its discharge end, the float B, having the depending spring M, screw-threaded rod K, provided with nuts C N, and weight K', the wire regulator F, and the cord G, having the weight H', substantially as set forth.

2. In combination with a windmill, the float B, the valve E, the cylinder G^2 , having the spring-plunger H, the cylinder $J' J''$, having the plunger L and piston R, and connected with cylinder G^2 by a web having port I, the regulator-wire F and cord G, having the weight H', and the discharge-pipe P, all constructed and arranged as and for the purpose set forth.

3. In the regulator attachment for windmills shown and described, the combination of the float B, having the screw-threaded rod K, nuts C and N, and weight K', with the valve E, consisting of the pipe or core Z, having ports d, case E', having the ports a and sleeved on pipe Z, and weighted lever D, having the perforated arm D', and pipe P, as and for the purpose set forth.

4. In an automatic regulator attachment for pumping-windmills, the combination of the

cylinders G^2 and $J' J''$, connected by a port, I, plunger H, having the stem S and spring O, plunger L, having the piston R, and neck Q, 40 forming a seat for plunger H, all arranged substantially as and for the purpose set forth.

5. In a regulator attachment for pumping-windmills, and in combination with the discharge-pipe P thereof, the valve E, arranged 45 on its discharging end in a tank and connected with and operated by a float in said tank, and the cylinders G^2 $J' J''$, connected with said pipe between its ends, said cylinders having, respectively, the plungers H and L, said plunger L being attached through the medium of its piston R to the regulating-wire of the mill, and the pump of the mill connected to said pipe P at its feed end, so that the increased pressure developed in said pipe by means of 50 the continued action of the pump after the closing of said valve by said float will operate said piston R and regulating-wire F and govern the sails of the mill, substantially as and for the purpose set forth.

6. In a regulator attachment for pumping-windmills, the valve E, consisting of the core Z, having the ports d, the case E', sleeved on said core or pipe, and having the ports a and arranged to partially rotate thereon to bring 55 said ports a and d in and out of line with each other, the weighted lever D, pivoted to said case, and having the arm D', and a float arranged to operate said valve, substantially as and for the purpose set forth.
